(57) CLAIM

We claim the ornamental design for a thermoacoustic imaging probe with outdents, as shown and described.

DESCRIPTION

FIG. 1 is a top-front-side perspective view of a thermoacoustic imaging probe with outdents.

FIG. 2 is a back-bottom-side perspective view thereof.

FIG. 3 is a front view thereof.

FIG. 4 is a top view thereof.

FIG. 5 is a right-side view thereof.

FIG. 6 is a left-side view thereof.

FIG. 7 is a back view thereof; and,

FIG. 8 is a bottom view thereof.

The broken line showing of a conduit connection represents environmental structure and forms no part of the claimed design. The remaining broken lines show portions of the thermoacoustic imaging probe that form no part of the claimed design.
